PANEL SECURING MECHANISM

William G. Landwier, Fayetteville, N. Y., assignor to Easy Washing Machine Corporation, Syracuse, N. Y., a corporation of Delaware

Application January 26, 1949, Serial No. 72,873

8 Claims. (Cl. 211—71)

1

This invention relates to panel securing mechanism, and more particularly to a construction having utility in the appliance field, including washing machines.

In washing machines having a construction similar to that shown in Little Patent 2,214,733, wherein spaced tubs are arranged side by side, it has been usual to provide a panel construction somewhat tangentially connecting the cylindrical side walls of the tubs to provide a smooth exterior side wall having flat intermediate panel faces and rounded ends formed by the tubs. Such panels have in the past been secured in place by tension bolts extending between opposite panels on opposite sides and threaded between the tubs at the approximate point of tangential contact of such tubs. Such construction has afforded difficulty in the assembly and disassembly of such panels, it being understood that the practice of mounting various control mechanisms upon the panels requires occasional disassembly of the panels for access and service.

It is an object of the present invention to provide a mechanism for independently securing the referred-to panels in position, the mechanism being simple in form, economical of manufacture, easy of installation, and at the same time permitting quick removal of the panels held in position thereby when desired.

The above and other objects of the invention will appear more fully hereinafter from the following detailed description when taken in conjunction with the accompanying drawings. It is expressly understood that the drawings are employed for purposes of illustration only and are not designed as a definition of the limits of the invention, reference being had for this purpose to the appended claims.

In the drawings, wherein like reference characters indicate like parts:

Figure 1 is a side elevation, parts broken away, illustrating the application of the invention to a washing machine;

Figure 2 is an enlarged broken section taken substantially on the line 2—2 of Figure 1;

Figure 3 is a detail sectional view taken substantially on the line 3—3 of Figure 2; and

Figure 4 is a perspective view of a spring clip shown in Figures 1 and 2.

Referring to the drawings, there is shown in Figure 1 a two-tub washing machine having a wash tub 10 and an extracting tub 12 mounted upon a base 14 having a skirt-like appearance, the whole being supported upon legs 16 and 18. The tubs 10 and 12 may be circular in section

2

and arranged side by side in substantially tangential relation, and in substantial accordance with the disclosure of the Little patent above referred to.

5 The base 14 comprises cylindrical or circular tub supporting hoops 19 and 21 arranged substantially tangential to one another, and filler side panels 20, each having an inwardly extending deck or shelf portion 22 having arcuate edges for engaging said hoops 19 and 21, but otherwise of substantially triangular shape. The shelf portions are secured to the hoops along their arcuate edges, as by welding to one or more struck out tabs as at 23. Each hoop in turn supports a tub, the tub 12 being shown as having an offset 25 seated upon a gasket mounted upon the rim 27 of the hoop 21. Mounted upon the rims of the tubs 10 and 12 is a deck 24 having an inner tub rim receiving flange 29 as for tub 12 and an inverted U-sectioned configuration 26 forming a marginal flange around the outer edge of the deck 24. The tubs 10 and 12 bear upon and against the hoops 19 and 21 and in turn the deck 22, and are held in position in part by tension bolts or stays 28 extending between the deck 24 and threaded fastening members 30 in the deck 22.

20 Side panels 32 are provided on either side of the washing machine, and are positioned in the deck 22 by means of spaced lugs 34 and 36 extending into semicircular struck out apertures 38 and 40 in the deck 22. Each of the side panels may have a horizontally extending offset 42 and curved horizontally extending stiffening ribs 44 and 46. The side edges 48 and 50 of each panel are adapted to bear against the cylindrical walls of the tubs 10 and 12.

25 For the purpose of securing the panel 32 in position, there is provided a spring clip 52 formed of spring strip stock. At its upper end, the clip has an upper inverted U portion 54 adapted to nest within the U configuration 26 and one or more reverse bends such as 56 and 58 to provide resiliency intermediate its length. Its lower end is provided with an inverted V hook 60 adapted to engage the upper edge 62 of the panel 32. It will thus be seen that when the parts are assembled as shown in Figure 2, with the spring clip under compression between the top panel edge 62 and the inverted U configuration 26, the panel 32 is urged downwardly into the proper position and inwardly, so that its edges 48 and 50 lie in snug engagement with the cylindrical side walls of the tubs 10 and 12.

30 The clip has adjacent the V hook 60 an in-

clined portion 64 extending to the reverse bends 58 and 56, which inclined portion may act as a cam in sliding the upper edge of the plate 62 along the inclined portion 64 until the upper edge 62 snaps into the V hook 66. It will be apparent that the panel may be readily removed, if desired, by flexing the clip in such a manner as to lift the cam portion 64 above the edge 62 of the plate 32, whereupon the plate 32 is readily removed to provide access to the space therebehind or to instruments such as a switch 65 or other device which may be mounted upon such panel.

The surface 64, as well as the loops 56 and 58, provide convenient finger holds for flexing the clip either for the purpose of assembling the panel in position or removing the panel in the manner described. At the same time, the loops 56 and 58 are concealed from view behind the skirt-like end 66 of the U configuration 26.

It will be readily apparent that by the clip means thus described, a panel such as 32 may be assembled or removed from the machine in a matter of seconds and that the clip utilized for the purpose may be economically formed from resilient spring strip stock so that the parts required for holding the panel in position are reduced to a minimum both as to number and cost.

Although a single embodiment of the invention has been illustrated and described, it is to be understood that the invention is not limited thereto. For example, such clip arrangement may be utilized to hold a panel-like means in other appliance constructions wherein the parts have a degree of similarity to those used herein for illustration. As various changes in the construction and arrangement may be made without departing from the spirit of the invention, as will be apparent to those skilled in the art, reference will be had to the appended claims for a definition of the limits of the invention.

What is claimed is:

1. In a device of the character described, a pair of vertically spaced decks, a supporting structure interposed between said decks and maintaining said decks in spaced and fixed relation, a vertical panel adapted to cover a part of and bear inwardly against said supporting structure, bearing means for supporting said panel upon said lower deck adapted to resist lateral movement, and resilient means interposed between said top deck and said panel, urging the top portion of said panel inwardly and downwardly.

2. In a device of the character described, a pair of vertically spaced decks, a supporting structure interposed between said decks and maintaining said decks in spaced and fixed relation, a vertical panel adapted to cover a part of and bear inwardly against said supporting structure, interlocking bearing means between said panel and said lower deck for supporting said panel thereon and holding the lower end of said panel against lateral movement, and resilient means interposed between said top deck and said panel, urging the top portion of said panel inwardly and downwardly.

3. In combination, a pair of adjacent tubs arranged substantially tangential to one another, a supporting frame for said tubs providing a deck in the space between said tubs adjacent the bottom level thereof, a top deck supported by the top rim of at least one of said tubs, stays interconnecting said decks, a vertical panel bridging the space between said tubs and having

substantially elemental contact therewith along its edges, interlocking means between said panel and said lower deck, and resilient means interposed between said top deck and said panel, urging the top portion of said panel inwardly and downwardly.

4. In combination, a pair of adjacent tubs arranged substantially tangential to one another, a supporting frame for said tubs providing a deck in the space between said tubs adjacent the bottom level thereof, a top deck supported by the top rim of at least one of said tubs, said deck having an inverted U section marginal edge, stays interconnecting said decks, a vertical panel bridging the space between said tubs and having substantially elemental contact therewith along its edges, interlocking means between said panel and said lower deck, and resilient means having a portion seated in said inverted U section and interposed between said top deck and said panel, urging the top portion thereof inwardly and downwardly.

5. In combination, a pair of adjacent tubs arranged substantially tangential to one another, a supporting frame for said tubs providing a deck in the space between said tubs adjacent the bottom level thereof, a top deck supported by the top rim of at least one of said tubs, and having an inverted U channel along its edge, stays interconnecting said decks, a panel bridging the space between said tubs and having substantially elemental contact therewith along its edges, interlocking means between said panel and said lower deck, and resilient means interposed between said top deck and said panel, urging the top portion thereof inwardly and downwardly, said resilient means comprising a resilient strip having a looped portion nesting in said U channel and a notch portion bearing against said panel.

6. In combination, a pair of adjacent tubs arranged substantially tangential to one another, a supporting frame for said tubs providing a deck in the space between said tubs adjacent the bottom level thereof, a top deck supported by the top rim of at least one of said tubs having a marginal edge interconnecting the rims of said tubs, tension means interconnecting said decks, a panel substantially tangentially bridging the space between said tubs and having substantially elemental contact therewith along its edges, interlocking means between said panel and said lower deck, and resilient means interposed between said marginal edge and the upper edge of said panel urging said last named means into interlocking position.

7. In combination, a pair of adjacent tubs arranged substantially tangential to one another, a supporting frame for said tubs providing a deck in the space between said tubs adjacent the bottom level thereof, a top deck supported by the top rim of at least one of said tubs having a marginal inverted U section edge extending substantially tangentially between said tubs, tension means interconnecting said decks, a panel laterally bridging the space between said tubs and having substantially elemental contact therewith along its edges, interlocking means between said panel and said lower deck, and resilient spring clip means having a portion nested in said U section and a portion bearing downwardly and rearwardly upon said panel.

8. In combination, a pair of adjacent tubs arranged substantially tangential to one another, a supporting frame for said tubs providing a deck

in the space between said tubs adjacent the bottom level thereof, a top deck supported by the top rim of at least one of said tubs having a marginal inverted U section edge extending substantially tangentially between said tubs, a tension means interconnecting said decks, a panel laterally bridging the space between said tubs and having substantially elemental contact therewith along its edges, interlocking means between said panel and said lower deck, and a resilient spring clip means having a portion nested in said U section and a portion bearing downwardly and rearwardly upon said panel, said clip means comprising a member formed of flat resilient strip stock having one end bent to form an inverted U nested in said U section, and an opposite end having an inverted V bear-

ing on said panel, the opposite ends being interconnected by a resilient central section having reversed folds.
